UNITED STATES PATENT OFFICE

1,924,666

SLICING MACHINE

Wilhelmus Adrianus van Berkel, Clarens, Switzerland, assignor to U. S. Slicing Machine Company, La Porte, Ind., a corporation of Indiana

Application January 18, 1930, Serial No. 421,624,
and in Germany February 21, 1929

18 Claims. (Cl. 146—103)

In meat slicing machines provided with an oscillating arm for the knife, it has been proposed to mount the bearings for the rocker arm in a yoke which extends above and transversely to the merchandise to be sliced and which also bridges the clamping plate so as to produce a strong construction of the machine. This construction, however, has the disadvantage that it impairs the accessibility to the clamping mechanism of the table.

One object of this invention, therefore, is to provide a slicing machine table which will eliminate the aforesaid disadvantage. This is accomplished by providing a slicing machine table which has a position of adjustment in close proximity to the cutting plane of the knife and another position remote therefrom and clear of the frame of the machine to a sufficient extent to permit the substance to be placed on the table and to be clamped thereon.

Another object of this invention is to provide aligning means for the table which will automatically determine the position which the substance to be sliced is to occupy on the slicing table when the slicing table is moved to the position adjacent the cutting plane of the knife.

A more specific object of this invention is to provide an abutment plate which is automatically positioned in a predetermined position relative to the slicing table when the slicing table is at a position remote from the cutting plane of the knife. This abutment plate automatically is moved to an inoperative position when the slicing table is moved into position adjacent the cutting plane of the knife.

Another object of this invention is the provision of a pivoted abutment plate which is automatically moved into a predetermined position relative to the slicing machine table as the table is moved from a position adjacent the cutting plane of the knife to a position remote therefrom.

A more specific object of this invention is to provide an abutment plate which automatically assumes the same relation to the slicing machine table while the latter is in inoperative position that the slicing knife occupies relatively to the table when the latter is in its operative position adjacent the cutting plane of the knife. This means comprises an abutment plate having a surface thereof adapted to be arranged substantially at right angles to the supporting surface of the slicing machine table. This surface occupies substantially the same relative position to the slicing machine table while the table is at an inoperative position that the adjacent surface of the slicing

knife occupies to the supporting surface of the table when the table is at its operative position.

Other objects of the invention will appear hereinafter, the novel features and combination being set forth in the appended claims.

In the drawing—

Fig. 1 is a fragmentary view partially in vertical section of a machine embodying my invention;

Fig. 2 is a section taken substantially along the line 2—2 of Fig. 1; and

Fig. 3 is a view of the essential parts of my machine as viewed from the left in Fig. 1.

The slicing machine comprises a frame having the base member 1 provided with the upstanding flanges 2 on opposite sides thereof. These flanges tend to brace the upstanding portions 3 which extend upwardly from the base 1 and also tend to brace the bridge section 4 which extends between the upstanding portions 3. This arrangement provides a very rigid frame structure for supporting the slicing machine knife.

The slicing machine knife is rotatably mounted on the end of an arm 6, the arm 6 being pivoted to a shaft 7 journalized in a suitable bearing in the bridge 4. The shaft 7 also has an internal gear 8 rigidly connected thereto. This gear is driven by the pinion 9 on the rotor shaft of the motor 10. The motor 10 is pivoted at 11 and has an arm 12 integral with or rigidly connected to the bracket which supports the motor and a spring within the housing 13 normally urges the motor in a clockwise direction about its pivot 11, thus insuring that the teeth on the pinion 9 and gear 8 will always remain in driving relation with each other. The shaft 7 also has a sprocket 14 rigidly connected thereto and a chain 15 is turned over this sprocket and over a sprocket 16 rigidly secured to the spindle 17 of the slicing machine knife 5, thus it will be seen that when the motor 10 is rotated the same tends to rotate the knife 5 about its axis, but no movement will be imparted to the arm 6 due to the rotation of the shaft 7 in view of the fact that the arm 6 is freely rotatable on the shaft 7. However, it is necessary to provide means for actuating the arm 6 and for this purpose, I provide a handle 18 on an extension of the arm 6. When it is desired to slice substances it is only necessary to move the arm 6 by means of the handle 18 about the shaft 7, the oscillations of the arm 6 effecting a feeding movement of the feed table for the substance being sliced through suitable feeding mechanism, not shown, as this feature is well known in the art to which this invention pertains.

On the frame of the machine and between the

- flanges 2 are mounted the spaced guide rods 19, these guide rods being hollow and provided with longitudinal slots 20 adjacent the inner sides of the hollow guide rods. The guide rods 19 are supported by means of the brackets 21 on the flanges 2. A table 22 is supported by the downwardly and upwardly extending members 23 having cylindrical lugs 24 on the extreme outer ends thereof. The cylindrical lugs 24 are guided within the hollow guide rod 19 so as to permit the table to be reciprocated or moved longitudinally of the guide rods from the full line position, shown in Fig. 1, to the dotted line position shown in that figure.
- 15 The under table 22 is provided with a feed table 50 diagrammatically shown in Fig. 1 and guided in any suitable manner on the upper surface of the table 22 as by the guides 58 in a direction toward and from the cutting plane of the knife. The feed table is provided with a feed nut 51 engaging the threads on a feed screw 52 provided with a ratchet wheel 53. The feed screw being rotatably mounted in fixed bearings on the side of the feed table 22 and adapted to be actuated by suitable mechanism when the substance table is at its operative position adjacent the cutting plane of the knife. Such a means is shown in my co-pending application Serial No. 421,623, filed January 18, 1930. The feed table 30 is also provided with uprights 55 carrying a clamping bar 56 which may be of any desired construction. The substance to be sliced is indicated at 57 and is clamped by means of the clamping bar against the feed plate 50. When the substance is placed on the table 22 and feed table 50 and clamped as illustrated in Fig. 1 with the forward edge of the substance against the gauge plate 32, it is obvious that when the table 22 is moved to the dotted line position shown in Fig. 1 the substance will have its forward edge in the cutting plane of the knife so that the very first slice which is cut by the knife will be of proper thickness. It is understood that the feeding mechanism advances the feed table 50 with a step-by-step movement toward the cutting plane of the knife as the substance is sliced.
- 40 When the table is in the dotted line position, shown in Fig. 1, the substance supported thereon is in a position ready to be sliced and after each slice is cut therefrom by the knife 5, the substance is advanced by means of the feeding mechanism into a position such that the next stroke of the knife 5 will sever an additional slice from the substance. Considerable difficulty has been experienced in positioning the substance on the table 22 while in its operative position due to the fact that the flanges 2 interfere with the proper manipulation of the clamping members or member for the material to be sliced, therefore, I propose to move the table 22 to the inoperative position shown in full line in Figs. 1 and 2, so that the table 22 is clear of the flanges 2 and the substance may be readily clamped on the table by means of the clamping mechanism.
- 45 When the table is moved to the inoperative position just described it is necessary to provide means for properly positioning the substance on the slicing table, so that when the table is moved to the operative position, the substance will be located in correct relation to the cutting plane of the knife. By properly positioning the substance on the table 22 slices of uniform thickness including the first slice, as well as each succeeding slice, will be cut from the substance by the slicing knife 5. Also if the forward edge of the substance to be

sliced is positioned on the table in such a position that the same will come in abutting relation with the inner surface of the knife, when the table is moved to its operative position, the next succeeding stroke of the knife will cut a slice from the substance of the proper thickness and will not cut a slice which is too thick or too thin and also the cutting operation will start immediately instead of necessitating a few strokes of the knife as is necessary if the substance is positioned too far to the rear of the slicing machine table. In order to accomplish properly the position of the substance on the table 22 I provide a positioning means which I will now proceed to describe.

It will be noted upon inspection of Fig. 2 that the flanges 2 are each provided with bosses 25. Each of these bosses carries a shaft 26 secured thereto by means of a pin 27. One of these shafts 26 carries an arm 28 which has a laterally extending lug 29 adapted to engage the stop 30 on the table 22 as is best illustrated in Fig. 1. The other shaft 26 carries an arm 31 and a plate 32 is secured at its lower end to each of the arms 28 and 31, it being understood that the arms 28 and 31 are free to rotate about the shafts 26 to enable the plate 32 to be moved from the full line position shown in Fig. 1 to the dotted line position shown therein.

It will be noted from an inspection of Fig. 1 that when the table is brought back to the inoperative position shown in full lines the stop 30 strikes the lug 29 and rotates the arms 28 and 31 in a counterclockwise direction from the dotted line position to the full line position and thereby positions the plate 32 at substantially right angles to the supporting surface of the table 22. Adjusting screws 33 are provided in each of the arms 28 and 31 adjacent the forward ends thereof and these adjusting screws are adapted to engage the laterally extending portions 34 at the forward edge of the table and by means of these screws I am able to adjust the position which the plate 32 will occupy relative to the supporting surface of the table 22. I prefer to adjust the inner surface or surface adjacent the table in the same position relative to the table that the cutting plane of the knife 5 occupies relative to the table when the table is in operative position. Therefore, if the substance is placed on the table 22 with the forward edge thereof in abutting relation to the surface of the plate 32 and the substance clamped on the table 22, while the substance is in this position, the forward edge of the substance being sliced will be in the cutting plane of the knife when the table is moved to operative position.

Any suitable means may be provided for limiting the forward movement of the table, that is a movement into the operative position shown in dotted lines in Fig. 1. The rearward movement is limited by engagement of the stop 30 with the lug 29 and by means of the adjusting screws 33 which limit the movement of the lug 29 in a counterclockwise direction about its path.

In order to move the table from the dotted line position to the full line position and vice versa, I provide a lever 35 pivoted at 36 to the base of the machine. This lever 35 has an operating handle portion 37 and carries an upwardly extending projection 38 adapted to slide within the longitudinal slot 39 formed in the boss 40 on the underside of the table 22. Therefore, it will be seen that as the handle 35 is moved about its pivot, the table will be moved longitudinally of the guide rods 19 from either an operative to an inoperative position or from an inoperative to an operative position depending upon the direc-

tion of rotation of the lever 35. Since it is only desired that the table occupy either one of the two extreme positions, I provide means for holding the lever 35 in either of its extreme limiting positions. This means comprises the telescoping members 41 and 42, the former being pivoted at 43 to an extension 44 integral with the bearing for the lever 35 and the latter being pivoted at 46 to the base of the machine. A spring 45 arranged within two telescoping members 41 and 42 normally urges the members longitudinally away from each other, so as to increase the distance between their pivotal connections with the lever and base, respectively. The pivots 36, 43 and 46 are so arranged that when the lever is in the full line position, shown in Fig. 2, the pivot 43 is arranged along one side of the line between the pivots 36 and 46 and so that when the lever is in the position which it occupies when the table is in its operative position, the pivot 43 will lie along the other side of the line between the pivots 36 and 46, thereby holding the table in its operative or inoperative position as the case may be.

It will be seen from the arrangement just described that when the table is in full line position, shown in Fig. 1, the plate 32 will be arranged substantially at right angles to the table 22 and the substance may be placed on the table with its forward edge against the plate 32 and clamped in this position. Thereafter the lever 35 may be operated so as to move the table to the dotted line position, shown in Fig. 1, to position the substance with its forward edge in the cutting plane of the knife. As the table moves to its dotted line position, the stop 30 moves therewith and permits the arm 28 to rotate in a clockwise direction about its pivot, thereby permitting the plate 32 to drop into an inoperative position beneath the table 22 in the manner best illustrated in Fig. 1 the plate 32 striking against the stop 47 formed by the opening in the front part of the frame. If desired any other suitable stop may be used for this purpose.

It will be understood that the term "operative position" or its equivalent means the position of the support adjacent the cutting plane of the knife which the support occupies when the substance is being sliced; while the term "inoperative position" means the position which the support occupies when the substance is being placed thereon for slicing purposes, and it is to be further understood that this latter position is a position in which the substance itself is not in a position to be sliced but necessitates the movement of the support to a position adjacent the cutting plane before the substance can be sliced.

I wish to have it understood that if desired the plate 32 may be moved into position from the side of as well as below the table 22 and I do not wish to limit the scope of my invention to a plate which is pivoted as it can be readily seen that the plate may be slid into position by a rectilinear movement with or without other type of movement which may be desired without departing from the spirit of this invention and the scope of the appended claims. Obviously those skilled in the art may make various changes in the details and arrangement of parts shown herein without departing from the scope of the invention as defined by the claims hereto appended and I wish, therefore, not to be restricted to the precise construction herein disclosed.

Having thus fully disclosed the embodiment of my invention what I desire to secure by Letters Patent of the United States is:

1. In a slicing machine the combination with a frame, of a slicing knife pivotally supported on said frame, a carriage mounted for reciprocation on said frame and adapted to occupy a position adjacent the cutting plane of said knife and also a position remote therefrom, a plate pivoted to said frame, and cooperating means connected to said plate and table for moving said plate into operative position adjacent and above one edge of said carriage as said carriage is moved to said remote position, and means for automatically moving said plate into an inoperative position out of the path of movement of said table when said table is moved to its position adjacent said cutting plane.

2. In a slicing machine, the combination with a substance support and a slicing knife movable relative to each other, said substance support being also movable toward and away from the cutting plane of said knife so that a substance may be located on said support while away from the cutting plane of said knife, and gauging means adapted to be automatically moved into operative position relative to one edge of said support when said support is moved to a position away from its operative position adjacent the cutting plane of said knife, said means for moving said gauge plate to operative position comprising co-operating abutments on said support and gauge plate which engage each other as said support moves to its position away from said cutting plane.

3. In a slicing machine, the combination with a slicing knife and a substance support movable relative to each other to cut slices from a substance located on said support, said support being also movable away from the cutting plane of said knife to an inoperative position, a gauge mounted for movement to and from a position beneath said support while said support is in its operative position adjacent the cutting plane of said knife, and means for moving said gauge plate into operative position adjacent the edge of said support when said support is moved to its inoperative position, said gauging plate having an operative connection with said support operable upon movement of said support to operative position adjacent the cutting plane of said knife for automatically moving said gauge plate to inoperative position below the substance support.

4. A device as claimed in claim 3 in which means are provided for moving said support to its operative or inoperative position and in which means is provided for moving said support to one or the other of said positions.

5. In a slicing machine, the combination with a frame, of a knife movable relative to said frame, guides on said frame, a support mounted on said guides for movement toward and away from the cutting plane of said knife, a lever operatively connected to said support for moving said support to a position adjacent the cutting plane of said knife and to a position remote therefrom, means for limiting the movement of said support in a direction towards the cutting plane of said knife and also in a direction away from the cutting plane of said knife, a spring for holding said support against either one or the other of said limiting means, a gauge plate mounted for movement into an operative position at one edge of said support when said support is at its position remote from the cutting plane of said knife so that a substance may be located on said support by means of said gauge plate and in the same position on said support as it is desired to have the substance occupy when the support is

at its operative position adjacent the cutting plane of said knife, and means for moving said gauge plate into said position when said support is at its remote position.

5 6. A device as claimed in claim 5 in which the gauge plate is operatively connected to said support for automatic movement into a position adjacent the edge of said support when said support is moved to its inoperative position and for 10 automatic movement to an inoperative position when said support is moved to its operative position.

15 7. In a slicing machine, the combination with a stationary frame, of a knife movable relative to said frame, guides extending in a direction transverse to the cutting plane of said knife, an under table slidably mounted on said guides, a stop for limiting the movement of said under table in a direction toward the cutting plane of said knife, a gauge plate movably mounted on said frame, an arm operatively connected to said plate, an abutment on said under table adapted to engage said arm as said under table is moved away from the cutting plane of said knife, the engagement of said abutment with said arm causing said gauge plate to move to a position adjacent that edge of said under table which lies adjacent the cutting plane of said knife when said under table is in its operative position adjacent 30 said cutting plane, and a stop for limiting the movement of said gauge plate and for also limiting the movement of said under table in a direction away from the cutting plane of said knife.

35 8. A device as claimed in claim 7 in which means is provided for maintaining said under table at its extreme positions adjacent the cutting plane of said knife and remote therefrom.

40 9. A device as claimed in claim 7 in which a feed table is provided on said under table and provided with clamping mechanism for clamping the substance on said under table in predetermined position with relation to said gauge plate and also thereby clamping the substance in predetermined relation to the cutting plane of said knife when said under table and feed table are moved to their positions adjacent said cutting plane.

45 10. A slicing machine comprising a slicing knife, a table mounted for movement to and from an operative position adjacent the cutting plane of said knife and a pivoted plate movable into a position adjacent one edge of said support when said support is away from the cutting plane of said knife to form an abutment adjacent that edge, said abutment acting as a gauge plate for positioning the substance in predetermined relation on said support, and operative connections between said plate and table for moving said plate into an inoperative position as the latter moves toward said cutting plane.

50 11. A slicing machine comprising a slicing knife, a support mounted for movement to a plurality of positions of adjustment, one of which is adjacent the cutting plane of said knife and another of which is remote from said plane, and an abutment plate operatively connected to said table to move automatically, due to said operative connections into an operative predetermined substance locating position adjacent to and above said support while said support is in said last mentioned position and to move automatically into inoperative position clear of said 55 slicing knife and the operative substance receiv-

ing space above said support when said support is moved to the other of said positions.

60 12. A slicing machine comprising a slicing knife, a support mounted for movement to a plurality of positions of adjustment, one of which is adjacent the cutting plane of said knife and another of which is remote from said plane, and a pivoted abutment plate operatively connected to said table to move automatically, due to said operative connections into an operative predetermined substance locating position adjacent to and above said support while said support is in said last mentioned position and to move automatically into inoperative position clear of said 65 slicing knife and the operative substance receiving space above said support when said support is moved to the other of said positions.

70 13. A slicing machine comprising a table, means for supporting the table for reciprocating movement, a slicing knife, means for moving said table into a position adjacent the cutting plane of said knife, a plate mounted for movement into operative position relative to said table for locating a substance on said table in a predetermined position thereon while said table is away 75 from said cutting plane, said plate being movable into a position underneath said table when said table is moved to its position adjacent said knife, and means for moving said plate to either 80 of said positions.

85 14. A slicing machine comprising a table, means for supporting the table for reciprocating movement, a slicing knife, means for moving said table into a position adjacent the cutting plane of said knife, a pivoted plate mounted for movement into operative position relative to said table for locating a substance on said table in a predetermined position thereon while said table is away 90 from said knife, said plate being mounted for movement into a position underneath said table when said table is moved to its position adjacent said knife, and means for moving said plate to either 95 of said positions.

100 15. A slicing machine comprising a table, means for supporting the table for reciprocating movement, a slicing knife, means for moving said table into a position adjacent the cutting plane of said knife, a pivoted plate mounted for movement into operative position relative to said table for locating a substance on said table in a predetermined position thereon while said table is away 105 from said knife, said plate being mounted for movement into a position underneath said table when said table is moved to its position adjacent said knife, and means for moving said plate to either 110 of said positions.

115 16. A slicing machine comprising a table, means for supporting the table for reciprocating movement, a slicing knife, pivoted arms carrying a positioning plate, a stop on said table, a projection on one of said arms, said stop having a path of movement such as to engage said projection when said table is moved 120 to the position in which the substance is to be placed thereon and being operative to move said plate when engaged by said projection into an operative position adjacent to and above one edge of said table, and a limiting stop for limiting the 125 movement of said plate into operative position.

130 17. A slicing machine comprising a table, means for supporting the table for reciprocating movement, a slicing knife, pivoted arms carrying a positioning plate, a stop on said table, a projection on one of said arms, said stop having a path of movement such as to engage said projection when said table is moved 135 to the position in which the substance is to be placed thereon and being operative to move said plate when engaged by said projection into an operative position adjacent to and above one edge of said table, and an adjustable stop for limiting the movement of said plate into operative 140 position.

145 18. In a slicing machine, the combination with a substance support and a slicing knife movable relative to each other to cut slices from a substance on said support, guides for guiding said support towards and from the cutting plane of 150

- 25 said knife, a gauge plate movable automatically to operative position adjacent one edge of said support as said support moves away from said cutting plane, said operative position being adjacent that edge of the support which is normally adjacent the cutting plane of the knife when said support is in operative position adjacent said knife, and said gauge plate when in operative position having one surface thereof located in the same relation to the adjacent edge of said support as that edge bears to the cutting plane of said knife when said support is in its operative position, whereby one side of the substance may be positioned against said surface of said gauge plate to locate that side of the substance in such a position on said support that when said support is moved to its operative position adjacent the cutting plane of the knife that side of the substance will lie in said cutting plane, said plate being so mounted and connected to said support as to move automatically to a position below said support as said support moves into operative position from an inoperative position and being substantially entirely arranged on the same side of said cutting plane as said substance support when said plate is in an inoperative position. 80
- 30 18. In a slicing machine, the combination with a slicing knife and a substance support movable relative to each other to cut slices from a substance located on said support, said support being also movable away from the cutting plane of said knife to an inoperative position, and a gauge plate mounted for movement to a position beneath said support while said support is in its operative position adjacent the cutting plane of said knife and for movement when said support is at its position away from said cutting plane to a position adjacent that edge of said support which is adjacent the cutting plane of said knife when said support is adjacent said cutting plane, said gauge plate being operatively connected to said support for automatic movement into an inoperative position below the substance support when said substance support is moved to its operative position adjacent the cutting plane of said knife. 85
